VISCOSITY TESTER

Albert G. Thomas, Alexandria, Va., assignor to
 Industrial Research Institute, University of
 Chattanooga, Hamilton County, Tenn.

Application November 15, 1945, Serial No. 628,783

8 Claims. (Cl. 73—55)

1

This invention relates to testers generally, and especially to oil testers for determining whether crankcase oil in motor vehicles is fit for further use, or not.

In operating motor vehicles, it is customary to change crankcase oil after a period of usage. This is ordinarily determined on a mileage basis. For motor cars, it has been a widespread practice to change oil after 1,000 miles of driving, more or less.

Another object is to provide a tester of greater accuracy by incorporation of means for automatically determining, in effect, the viscosity index of any oil tested.

A further object is to provide a simplified timing device for actuation of the oil cup valve, or for other purposes.

An additional object is to provide a simplified mixing chamber for oil and diluent before it passes over a screen for a dirt test.

Other objects will appear in the specification.

In the drawings:

Figure 1 is a front elevation, with casing in section, of a simplified oil tester in which various parts are combined to serve several functions.

Figure 2 is a top plan view, with top cover partly broken away, showing the timing device, hinged cap, and mixing elements of the tester of Figure 1.

Figure 3a shows an edge view of a spring catch.

Figure 3 is a front elevation showing another form of timing device and a special viscosity cup and associated mechanism for effectively compensating viscosity determinations for variable viscosity indices of oils under test.

Figure 4 is a fragmentary elevation of a viscosity cup with two needle valves attached to one operating arm.

In Figure 1, casing 1 is fastened to cross plate 2 and short plate 3 is screwed to casing 1. Top cover 4, having openings for rods 5 and 6 and for funnel 7 with cap 8 pivoted at 9 to a lug on the cover, is provided and may be detachable. Rods 5 and 6 are provided with top buttons 10 and 11. Cam 12, attached to cap 8, is positioned to engage pin 13 on rod 5 to lift this rod when the cap is swung about pivot 9.

Rod 5 may be of rectangular cross section, to prevent rotation, and is vertically movable in openings in cover 4, plate 2, and plate 3. Spring 14, attached at its upper end to rod 5, and resting on plate 3, normally holds the rod in the position shown with attached flexible valve arm 15 holding resilient valve 16 below the bottom end of glass or other transparent viscosity tube 17. Valve 16 may be cemented or otherwise fastened to arm 15 and may consist of synthetic rubber or other material not easily affected by oils. Spring 18, surrounds rod 5 and is under slight compression between plate 3 and arm 15 so that it

2

assists gravity in normally keeping valve 16 below the end of tube 17. This tube is held in position by clamp 19 on plate 3 and by openings in plate 2 and the bottom 20 of overflow trough 21 which may be screwed to plate 2. A packing gland may be provided to prevent leakage around the upper end of tube 17.

Piston 22, which may include a leather washer, is fastened to the lower end of rod 5 and is vertically movable in cylinder 23 fastened in tank 24 through its bottom. This tank is for the purpose of holding diluent or cleaning fluid which may be kerosene if desired. It is attached to casing 1 or to suitable framework by means of lugs 25.

Opening 26 in cylinder 23 allows fluid to fill the cylinder when the piston is in the lifted position shown.

Tube 27 leads into the lower part of cylinder 23 and carries fluid to nozzle 28 to clean tube 17, to tube 65 for photocell unit 29 to clean this unit, to mixing bucket 30 through nozzle 32 and to cup 31 through a nozzle on the rear side of nozzle 32.

Viscosity cup 31 is preferably of thin metal or of material of poor heat conductivity so that excessive heat will not be taken from the oil or other fluid under test. It is fastened to trough 21, preferably through heat insulation material if the trough is of metal. The cup has central metering tube 33 screwed into an opening. This tube extends inside the cup for a vertical distance which may be about one fourth the height of the cup. Drain opening 34 is also provided in the bottom of the cup and is adapted to be closed by synthetic rubber valve 35 attached to flexible arm 36 which is fastened to collar 37 vertically slidable on rod 5 above supporting pin 38 on the rod. A suitable slot can be cut in plate 2 to allow pin 38 to pass through when rod 5 is depressed. Needle valve 40, pivoted to arm 41 at 39, normally rests against the top of tube 33 to close it, a suitable guide being provided.

Bucket 30 is supported by attached pivot pins 42 resting in suitable slots in the side walls of trough 21 (Figure 2), and by pin 43 attached to the trough. Spiral spring 44, attached to the trough and to a pin 42, may be used to hold bucket 30 normally against pin 43.

Trough 21 has inner wall 45 the top edge of which is below pivots 42 so that fluid from bucket 30 will drain out of the bucket into compartment 46 when bucket 30 is rotated in clockwise direction by being struck with the lower end of starter rod 6. This rod is vertically slidable in guide 47 attached to cover 4. Tension spring 48, attached to guide 47 and rod 6, normally holds the rod in the position shown, a suitable stop being provided. Arm 49, with attached cam 50, is attached to rod 6 and extends over so that it will strike

release 51 of timing device 52 pivoted at 51a, when rod 6 is depressed.

Trough 21 is extended as shown, to catch drainage from cup 31 and has attached drain pipe 53 to direct this fluid into can 54 resting on the bottom plate 55 of the casing. Similarly, drainage from tube 17 will fall into can 54.

Coiled tube 56 leads into compartment 46 and is connected into photocell unit 29 so that it will conduct the mixture of diluent and oil or other fluid from double compartment bucket 30 to screen 57 of relatively fine mesh. The two compartments 30a and 30b of bucket 30 are formed by partition 30c (Fig. 2).

Photocell or dirt-testing unit 29 comprises transparent glass or plastic cylinder 58 containing photoelectric cell 59 pressed against transparent wall 59 by threaded plug 61 through which conductors 62 may be passed to be connected to cell 60. These conductors are connected with electrical instrument 63 which may be a microammeter or milliammeter. Unit 29 may be supported by a bracket or by the connected tubes.

Screen 57 is supported on drain pipe 64 passing through the cylinder wall and upon pipe or tube tube 65 connected with tube 27 and also passing through the cylinder wall. Additional supports for the screen may be provided and it is preferable to provide another drain, connected with tube 64 and entering the cylinder above screen 57. This screen may be slotted near its lower end.

Electric lamp 66 is attached to reflector 67 which is fastened to transparent top plate 68 which is screwed to the top edge of the cylinder 58.

Funnel 7 is suitably fastened and has attached copper or other metal coil 69 the end of which is positioned to drop fluid from funnel 7 into cup 31. This coil is suitably insulated and is wound with heating wire 70 which may be supplied with current through the terminals shown, including thermostat 71.

Stem 72 of dial type thermometer 73 is placed in cup 31 to indicate the temperature of the fluid under test. This thermometer and instrument 63 are supported by the front casing.

Arm 41 is pivoted to vertical plate 74 of the timing device at 75. This plate is integral with horizontal base plate 76. Spring strip 77, with a projecting edge adapted to rest upon shelf 78 attached to plate 74, is fastened to arm 41 (see Fig. 3a). The lower end of this strip is struck by cam 79, attached to pulley 80, when weight 81 fastened to cord 82 passing around the pulley, is allowed to fall and so to rotate the pulley and coaxial gear 83, by means of ratchet 84 on an edge of the pulley striking notches in the face of gear 63. Rod 85 extends outwardly and is bent at the rear and attached to the face of pulley 30. This arm is adapted to be struck by arm 86 attached to rod 5 when the rod is depressed.

Knob 87 has attached pointer 89 and is manually rotatable on shaft 88 which is rotatably fastened to plate 74. This shaft supports knob 87 and gear 83. A suitable friction device such as a resilient strip, is fastened to knob 87 and presses against shaft 88 so that the knob may be manually adjusted in angular position on the shaft but the shaft will rotate the knob and arm 89 in counterclockwise direction (Fig. 1) when weight 81 is allowed to fall slowly.

Gear 83 drives escapement 90, pivoted to plate 74, by means of toothed wheel 91 which in turn is driven by gear train 92 having suitable bear-

ing on shafts fastened to plate 74. The escapement regulates the rate of fall of weight 81 and therefore the rate of rotation of pulley 80.

Arm 89 is bent so that it will strike resilient strip 77 and force it off the supporting shelf 78, when arm 89 is rotated in counter-clockwise direction past the strip.

The circuit to lamp 66 and to any other lamps which may be used to illuminate the device, is controlled by toggle switch 93 mounted on the casing or any convenient support. When starter rod 6 is depressed, cam 50 on arm 49 strikes the arm of switch 93 and forces it to the left to close the circuit. When clearing rod 5 is depressed, cam 94 on this rod strikes the switch arm and forces it to the right to open the switch.

The heating circuit including resistor 70 may be provided with a suitable switch. This switch would ordinarily remain closed when it is desired to use the tester so that the coil 69 will be warmed and cup 31 will be maintained at a moderate temperature.

In operation, cap 8 is lifted, which results in valves 35 and 16 closing the drain opening of cup 31 and the bottom of tube 17, respectively, since cam 12 strikes pin 13 and lifts rod 5 as the cap is rotated. The rod is held in the lifted or "up" position by spring 96, fastened to plate 2, pressing against groove 97 in the rod. Then a small sample of oil, say, is placed in funnel 7, from which it flows through tube 69 and becomes heated. Cap 8 is then closed. The heated oil drops into cup 31 and flows over attached lip 95 and into compartment 30a of bucket 30. The overflow from this bucket spills over the lower bucket edge and into trough 21 from which it passes through tube 53 to can 54. Bucket compartment 30b is normally filled with diluent from nozzle or tube 32, when rod 5 is depressed to clear the mechanism and to actuate pump piston 22.

After thermometer 73 reaches a steady indication, the temperature of the oil is read and arm 89 is rotated relative to a calibrated temperature scale (not shown) until the arm, or pointer, is in register with the temperature mark on the scale equivalent to the reading of the thermometer. Button 11 is then pushed down to depress starter rod 6. This causes arm 49 to strike one end of pivoted catch 51 so that it lifts its attached pin from gear 92a, and weight 81 accordingly starts to fall with the result that cam 79 quickly lifts strip 77 and arm 41 so that needle valve 40 is raised and oil starts to flow through orifice or metering tube 33. Bent strip 77 will remain in elevated position on shelf 78 until arm 89, rotated by the weight in counterclockwise direction, strikes it and knocks it off the shelf, the resiliency of the arm making this possible. The weight of the arm, or a spring if desired, will then force needle valve 40 down against the conically reamed upper end of tube 33 to close the orifice and so to stop flow of the oil.

The time interval between the opening of the valve by cam 79 and its closing by arm 89 will depend upon the angular position of the latter arm, since escapement 90 causes the weight to rotate the gears at uniform rate. The friction between knob 89 and shaft 88 is sufficient to prevent slippage when arm 89 strikes strip 77 but not enough to prevent setting of the arm relative to the temperature scale. The scale is calibrated so that the hotter the oil, the less time will valve 40 remain lifted so that viscosity variation due to temperature can be compensated for

by changing the time interval of flow through the orifice.

The oil builds up in tube 17 to heights inversely proportional to viscosity and tube 17, or an associated scale, can be marked off in bands representing S. A. E. numbers as shown, or Saybolt seconds viscosity, as desired.

When rod 6 is depressed, it strikes the right edge of bucket 30 and forces it over, against spring tension, so that the oil in compartment 30a and the diluent in compartment 30b are dumped into compartment 46. The mixture of oil and diluent then flows through coil 56, in which it is further mixed, and onto screen 57 through which it flows, leaving any relatively large dirt particles trapped on the screen or in the interstices. This dirt will obstruct light from lamp 66 so that the amount of light striking photoelectric cell 59 will be in inverse proportion to the amount of dirt trapped by the screen. Instrument 63 will therefore indicate the degree of dirtiness of the oil and the scale can be calibrated in any desired way such as in bands reading Danger, Doubtful, and Safe.

A slot may be made in the screen near its lower edge to allow debris to be washed away by fluid from tube 65. It will be observed that this fluid tends to kick the dirt upward and another stream above the screen could be used to help wash away the dirt.

My mixing the oil with diluent before passing through the screen, the effects of temperature differences are minimized as, otherwise, cold oil would tend to form thick films over the screen. I have found that equal parts of oil and a diluent such as kerosene is a good proportion.

It should be noted that this is not merely a color test but uses actual dirt content as the determining factor. In fact, oil that is so dark that it appears black can be tested and the indication will be Safe if the color is due merely to colloidal carbon or the like. If, however, the container is thoroughly shaken so that sludge, dirt, and such debris are mixed into the oil before testing, then the indication will be Danger if the oil is in that condition.

When the test is completed, button 10 is pressed down so that valves 35 and 16 open the drain to cup 31 and tube 17, respectively, and piston 22 forces cleaning fluid from tank 24 through tubes 27, 28, 32, and 65. Rod 5 can slide through sleeve 37 when this is stopped by arm 36 striking the edge of trough 21. This causes fluid to clean tube 17, cup 31, and screen 57 and associated parts, and at the same time fills compartment 30b with the diluent for the next test. Other parts such as compartment 46 can be cleaned too.

The depressed clearing rod 5 also carries arm 86 downward so that it strikes pin 85 on pulley 80 and forces this pin down to the position shown. This causes rotation of the pulley in a clockwise direction to lift weight 81 to starting position. Ratchet 84 allows the clockwise rotation of the pulley. Likewise, when rod 5 is depressed, cam 94 strikes the arm of toggle switch 93 and so cuts off the current to lamp 66. When rod 5 is released, spring 14 returns it to the position shown. Spring 48 similarly returns rod 6 to starting position, when rod 6 is released.

The pointer of thermometer 73 and arm 89 could be adjacent or coaxial so that arm 89 could be rotated until it is in register with the thermometer pointer. This would simplify the setting for temperature of the fluid under test.

In Figure 3, is shown a device for compensating

for different rates of change of viscosity with temperature. If the temperature scale of the tester of Figure 1 is calibrated for an asphaltic base oil, it will not compensate correctly for a paraffin base or Mid-Continent base. Similarly, if it is calibrated for a paraffin base oil, it will not compensate correctly for an asphaltic or Mid-Continent oil. In practice, a scale which is a compromise of the three scales works out very well within temperature limits of say 100° F. to 160° F.

In case greater accuracy is desired, however, the compensator shown in Figure 3 may be used. Equivalent parts are given the same numerals as in Figures 1 and 2. Viscosity cup 31 is supported on plate 2 by bracket 2a and has orifice or metering tube 33 and similar metering tube 33a. Valves 40 and 40a and operating arms 41 and 41c, pivoted to plate 74 at 75, and 75a, respectively, are provided. Drain valve 34, operated by mechanism, as shown previously, is provided.

Viscosity tube 17, which may be marked off in S. A. E. bands as indicated, passes through an opening in plate 2, being packed by gasket 98, if desired. The lower end of this tube is packed or cemented in the flanged upper end of cylinder 99, supported by plate 3 through which it passes. Drain opening 100 in cylinder 99 allows oil or other fluid in tube 17 to discharge when piston 101, vertically movable in cylinder 99, is below the opening. Piston 101 is fastened to arm 102 integral with rod 103 which is vertically slidable in guide 104 attached to a convenient part of the device. This rod passes through opening 105 in plate 3 and has notches 106 and 107, one above the other as shown. Catch 108 is pivoted to a lug on plate 3 and has a spiral spring normally urging the catch to engage notch 106. Arm 109 is integral with the catch and is positioned to be struck by weight 81 when near the bottom of its path. Similarly, spring catch 110, pivoted to a lug on plate 3, has integral arm 111, and is normally urged to engage notch 107.

Starting rod 6, shown in fragmentary fashion, will strike arm 111 to move catch 110 out of notch 107, when the rod is depressed and clearing rod 5, also shown in fragmentary manner, will strike arm 102 to force piston 101 and rod 103 downward, when that arm is depressed.

The upper end of rod 103 is chamfered and enters cylinder 112 which is supported on flange 113 of rod 103, acting as a valve. Cylinder 112 has inlet 114 and catch-pan 115 to gather fluid from metering tube 33a and to guide it through opening 114 into cylinder 112. Opening 116 in plate 2 is sufficiently large to allow pan 115 free vertical movement.

Piston 117 is vertically movable in cylinder 112 and is attached to arm 118 which extends over cam 119 on shaft 88 which has rotary bearing in plate 74 as before. Cam 79, which lifts arm 41 by striking cam 41a, is integral with gear 83 which may be fastened to disc 80a or connected through a ratchet. For convenience, the reset mechanism is not shown but may be similar to that illustrated in Figure 1.

Disc 80a, having cam 80b to strike cam 41b integral with arm 41c, is adapted to lift that arm for a short time interval, determined by the speed of rotation of shaft 88 and the circumferential length of cam 80b. Pulley 80 extends out from disc 80a, and arm 89 adapted to strike resilient arm 77 to knock it from shelf 78, is attached to cam 119, on one face, so that the arm 75 will not interfere with the operation of the cam,

As before, there is a friction connection between shaft 88 and the knob (not shown) which is attached to the forward face of cam 119. The starting mechanism or latch may be similar to that shown in Figures 1 and 2.

Shaft 88 is driven by gear 83 in counterclockwise rotation, either directly or through a ratchet. Cam 119 and arm 89 are rotated by the shaft or shaft and knob, by means of friction as described. The escapement 90 and cooperating toothed wheel regulate the rate of rotation of gear 83 by falling weight 81, insuring uniform rotation.

In operation, a sample of oil, say, is placed in cup 31 and the temperature is read on a suitable instrument, as before. Then arm 89 is set relative to temperature scale 89a, being positioned closer to cam 79 the higher the temperature. This scale is calibrated to compensate exactly for changes of viscosity of a chosen oil of a particular viscosity index, say a Mid-Continent base oil. Then, if the valve is open, oil will flow through tube 33 and will rise in viscosity tube 17 to heights inversely proportional to the viscosity of the oil, before the flow is stopped by the timed valve. After the starter is released, cam 41a is struck by cam 79 and strip 77 is lifted onto shelf 78 so that valve 40 is lifted until arm 89 is rotated around and strikes strip 77 a sidewise outward blow and knocks it off shelf 78 so that valve 40 is dropped to stop flow of the oil through metering tube 33.

Since scale 89a was calibrated with oil of the same base or viscosity index, the heights to which oil of the same base will build up in tube 17 will be very accurate indications of viscosity, since the temperature compensation is accurate. The scale on, or adjacent to tube 17 may be in S. A. E. numbers or in Saybolt seconds.

If, however, an oil of a different base, such as asphaltic or paraffinic is tested, scale 89a will not accurately compensate for variations of temperature of the oil. These oils change viscosity at different rates, with respect to temperature change, as compared to some Mid-Continent oil, for instance.

In order to compensate for the varied viscosity indications due to different bases of oils, when temperatures vary, the mechanism shown has been added. As cam 79 is rotated, cam 80b on disc 80a is likewise rotated counterclockwise to strike cam 41b to lift arm 41c and valve 40a for a predetermined, relatively short time interval. This interval may be the same for all tests. This results in flow of the oil under test through metering tube 33a for the aforesaid interval and this oil strikes scoop 115 and flows through passage 114 and into cylinder 112. The initial position of rod 103 was so that catch 101 engaged notch 107 and piston 101 was accordingly held below opening 100 so that drainage from tube 17 could take place through opening 100. At the same position, scoop 115 or a lug on cylinder 112 could strike a bracket depending from plate 2 so that valve 103 would be lowered to allow drainage from cylinder 112.

When starter rod 6 is depressed, arm 111 is struck so that catch 110 releases rod 103 which is pulled up by tension spring 120, attached to the rod and to plate 3, and piston 101 closes opening 100 and valve 103 is quickly lifted to seal the bottom of cylinder 112 against leakage. Spring catch 108 falls into notch 106 to stop the upward movement of rod 103 in the position shown.

Spring 121, attached to arm 118 and to plate 2, 75

tends to pull piston 117 down into cylinder 112 but is normally prevented from moving the piston by latch 122 pivoted at 123 to lug 124 fastened to plate 2. A suitable spring fastened to latch 122 and to lug 124 normally tends to hold the latch in vertical position shown, supporting arm 118.

Cam 119 is so shaped that it allows arm 118 only slight downward movement, when released, for high temperatures, and increasing downward movement of the arm before striking the cam as a stop, as the oil temperature under test is lower. The cam shape is chosen so that the calibrating oil which flows into cylinder 112 as a result of passing through tube 33a while the valve 40a is lifted, will rise in cylinder 112 to heights increasing with the temperature of the oil and just sufficient to meet the bottom of piston 117 when arm 118 is supported on cam 119. It will be observed that arm or pointer 89 is attached to cam 119 so that when the arm is set relative to temperature scale 89a, for the temperature of the oil under test, cam 119 is correspondingly rotated so that the topmost position of the cam at that temperature will be such that the bottom of piston 117 will just touch the surface of the calibrating oil which has flowed into cylinder 112. Therefore, when weight 81 nearly reaches its lowest position and strikes arm 109 to cause catch 108 to rotate out of notch 106 to release rod 103, there will be no movement of rod 103 for the calibrating oil, since the cylinder chamber is filled to the level of the bottom of piston 117.

Spring 121 is chosen of greater strength than spring 120 so that it can, if not stopped, force rod 103 down against the upward pull of spring 120. Latch 122 is struck by cam 125 on gear 83 when the gear is near its maximum rotary counterclockwise displacement. Therefore latch 122 is knocked from under arm 118 at this point and spring 121 pulls piston 117 down until arm 118 strikes cam 119. Opening 114 in cylinder 112 is covered with slight downward movement of the piston. Arm 118 may be lifted back on latch or prop 122 by means of arm 126 which is lifted by a suitable lever operated by clearing rod 5. The dimensions of tube 33a, cam 80b, and cylinder 112, are so chosen that the maximum flow of any fluid likely to be tested will not fill the cylinder quite up to opening 114. It will be seen then that as long as any oil tested has the same viscosity index as the calibrating oil, the rod 103 and consequently piston 101 will remain in position so that the level of the test oil in tube 17 will indicate true viscosity.

Now suppose that the oil tested varies in viscosity at a greater rate than the calibrating oil, i. e., it becomes less viscous for a given temperature. Then, during the time that valve 40a is lifted, the test oil will rise higher in cylinder 112 than the calibrating oil would and, when arm 118 is released so that it is pulled down against cam 119, properly set for the temperature by pointer 89 and scale 89a, the piston 117 will strike the oil in cylinder 112 and will force rod 103 and piston 101 down for a distance equal to the difference between the height of rise of the calibrating oil and that of the test oil, in cylinder 112, for the particular temperature involved. This lowering of piston 101 will correspondingly lower the height of the oil in tube 17 so that a compensating effect is achieved. The diameter of piston 117 may be the same as the diameter of piston 101, or otherwise.

In similar manner, but in the reverse sense, if the oil under test is more viscous with changing temperature than the calibrating oil, the test oil will not rise sufficiently high in cylinder 112 to meet the bottom of piston 117 and so spring 120, when catch 108 releases rod 103, will pull that rod and piston 101 upward until the oil in cylinder 112 strikes the bottom of piston 117. The level of the oil in tube 17 will therefore be lifted to indicate corrected viscosity.

It is obvious that a fixed travel of piston 117 could be used and valve 40a could be attached to bar 41, as shown in Figure 4, so that the time interval of flow through tube 33a would be substantially the same as that for the flow through tube 33. In this case, the time of opening of valve 40a would be adjustable for temperature.

While I have shown several modifications of the invention, I realize that many variations can be easily contrived by others without departing from the broad concepts I have disclosed.

What I claim is:

1. In a viscosity testing device, in combination, a container for fluid, a metering orifice in said container for discharge of fluid therefrom, a valve for said orifice, means including timing means for opening said valve for predetermined intervals of time, another orifice in said container, another valve for said other orifice, means including said timing means for opening said other valve for a predetermined interval of time, a transparent tube to receive fluid discharged from said metering orifice, a scale for indicating viscosity as determined by height of fluid in said tube, valve means for said tube including a piston to control flow of fluid therefrom, movable means to operate said valve piston, a vessel carried by said movable means and adapted to receive fluid discharged from said other orifice, a piston movable in said vessel to trap said fluid therein to cause movement of said movable means said tube valve means comprising a cylinder having an aperture and said valve piston slidable in the cylinder to cover said aperture and also to vary the viscosity indications in accordance with the movements of the vessel, and stop means settable in accordance with the temperature of said fluid for limiting movement of said piston.

2. Same as in claim 1, and including means for moving said vessel piston.

3. Same as in claim 1, the vessel carried by said movable means having an inlet and an exit port for said fluid.

4. In a viscosity testing device, a container for fluid, a metering orifice in said container for discharge of said fluid therefrom, a valve for said orifice, means including timing means for opening said valve for predetermined intervals of time, another orifice in said container, another valve for said other orifice, a movably mounted vessel to receive discharge of fluid from said other orifice, a piston movable in said vessel, means responsive to quantity of fluid discharged from said metering orifice for indicating viscosity, means including a movable member connecting said viscosity indicating means with said vessel so that movements of said vessel effect proportional movements in said viscosity indicating means, and means including a movable member connecting said timing means with said other valve to open said other valve for a predetermined interval of time before opening of said metering orifice valve.

5. In a viscosity testing device, a container for fluid, a metering orifice in said container for discharge of fluid therefrom, a valve for said orifice, timing means including a rotatable member for opening said valve for predetermined intervals of time, a temperature scale on said rotatable member, another orifice in said container, another valve for said other orifice, means responsive to quantity of fluid discharged from said metering orifice for indicating viscosity, means including a movable member connecting said timing means with said other valve to open said other valve for a predetermined interval of time before opening of said metering orifice valve, means movable in proportion to the quantity of fluid discharged from said other orifice, means including a movable member connecting said movable means with said viscosity indicating means to effect movement of the latter in accordance with movements of said movable means, and means for limiting the degree of movement of said movable means in accordance with the temperature of said fluid.

6. In a viscosity testing device, in combination, means including an orifice for testing viscosity of a fluid as determined by quantitative flow of said fluid through said orifice during a predetermined period of time, means including a scale for indicating viscosity, other means including an orifice and responsive to the viscosity index of said fluid as determined by quantitative flow of said fluid through said second named orifice during a predetermined period of time, and means including a movable member connecting said means responsive to viscosity index with said viscosity indicating means to effect displacement of said viscosity indicating means in accordance with the viscosity index of said fluid.

7. Same as in claim 6, and including means incorporating a temperature scale, a member settable relative thereto, and an element varied in position by movement of said member to limit movement of said other means for adjusting the degree of responsiveness of said other means according to temperature of said fluid.

8. In a viscosity testing device, in combination, means for testing viscosity of a fluid as determined by relative flow of said fluid with respect to said means, means for starting said flow and stopping said flow after a predetermined interval of time, means including a scale for indicating viscosity, other means for determining the viscosity index of said fluid as a result of relative flow of said fluid with respect to said other means, means for starting said flow and stopping said flow with respect to said other means after a predetermined interval of time, means including temperature scale means and timing means settable relative thereto for predetermined intervals of time, and means including a movable member connecting said viscosity indicating means with said other means to effect displacement of said viscosity indications in accordance with the viscosity index of said fluid.
